UNITED STATES PATENT OFFICE.

ALVIN A. DAUGHERTY, OF NEW YORK, N. Y.

APPARATUS FOR PRODUCING GASOLENE AND OTHER PRODUCTS FROM HYDROCARBONS.

1,353,638.

Specification of Letters Patent. Patented Sept. 21, 1920.

Application filed May 23, 1917. Serial No. 170,465.

To all whom it may concern:

Be it known that I, ALVIN A. DAUGHERTY, a citizen of the United States, residing at New York city, in the county of New York 5 and State of New York, have invented certain new and useful Improvements in Apparatus for Producing Gasolene and Other Products from Hydrocarbons; and I do hereby declare the following to be a full, 10 clear, and exact description of the invention, such as will enable others skilled in the art to which it appertains to make and use the same.

This invention relates to an apparatus for 15 producing gasolene, etc., from hydrocarbons and has for its object to provide a method which will be simple in its nature, comparatively easy to carry out and less expensive in operation than those which have been here- 20 tofore proposed.

With these and other objects in view the invention consists in the novel steps and combinations of steps constituting the process, all as will be more fully hereinafter 25 disclosed and particularly pointed out in the claim.

Referring to the accompanying drawing forming a part of this specification in which the figure is a diagrammatic view illustrating 30 one form of apparatus suitable for carrying out the invention, 1 indicates any suitable apparatus for heating kerosene, crude oils, distillates and other hydrocarbons, such for example, as that described and claimed 35 in my copending application #154362, filed March 12, 1917, and entitled Process of and apparatus for heating oil.

Said apparatus is suitable for heating the hydrocarbon raw material up to a temperature 40 of say from 800° F. to 900° F. or 1000° F. or even 1200° F., and it is also constructed in such a manner as to make it capable of standing pressures of from say 300 pounds, 400 pounds, or even 600 or 1000 45 pounds to the square inch.

The kerosene or other hydrocarbon after having passed through said apparatus is led off through the pipe 2, and preferably at a pressure of say about 500 pounds to the 50 square inch, and at a temperature of say about 800° F. or 900° F. Said pipe 2 communicates with the still 3, into which the oil or hydrocarbon under pressure is sprayed, as through the pipe 4 having a plurality of fine jets or nozzles 5.

The pressure of the sprayed hydrocarbon in the still 3 is preferably reduced to substantially that of the atmosphere, or it may be even reduced below that of the atmosphere, by applying suction as by the apparatus 6 to the outlet or take-over conveyer 7. 60

After the hydrocarbon has been thus sprayed into the still 3, a portion of the same may collect in the form of a liquid, as indicated at 8, but the larger portion thereof appears in the form of a vapor which passes through the pipe 7 into the condenser 9. 65

Any portion 8 which may collect in the form of a liquid may be suitably heated as 70 by the furnace 10, and it is found in practice that, when kerosene is used, it substantially all evaporates, and its resulting vapor is likewise passed over through the pipe 7 into the condenser 9. 75

In practice, I find it very convenient to continue the fire in the furnace 10 under the still so that the process becomes continuous, in that the liquid 8 is evaporated about as fast as it collects in the still 3. 80

When residuums heavier than kerosene are employed there may be some material left in the still which it is not convenient to evaporate, and such materials may be drawn off as through the pipe 12. 85

The vapors passing into the condenser 9 are readily condensed into the form of a liquid which is found to be gasolene of a very pure quality. Said gasolene is conveniently drawn from the condensers 9, as 90 by the pipe 13, into shipping containers.

It should be observed that the heating of the original kerosene in the apparatus 1 is conveniently carried to a point higher than that which it would probably experience when used in internal combustion engines, and it has been observed in practice that when this product from the condenser 9 is employed in internal combustion engines it seems to deposit less carbon than gasolene which has been subjected to a less temperature. 95 100

It is obvious that those skilled in the art may vary the details of construction of the apparatus as well as the steps and combinations of steps constituting the process, without departing from the spirit of the invention, and therefore, I do not wish to be limited to the above disclosure except as may be required by the claim. 105 110

What I claim is:—

In an apparatus for producing gasolene from hydrocarbon oils the combination of means for heating said oils to temperatures above 700° F. and at pressures exceeding 300 pounds to the square inch; means for permitting said heated oils to suddenly expand into vapors at substantially the pressure of the atmosphere, a suction apparatus

for removing said vapors from said last named means; additional heating means for vaporizing any liquid residue that may collect in said last named means; and means into which said suction means discharges for condensing into a liquid form the vapors thus produced, substantially as described.

In testimony whereof I affix my signature.

ALVIN A. DAUGHERTY.
